Inventor:
Francis S. Garford,

By C. C. Hines,

Attorney.

UNITED STATES PATENT OFFICE.

FRANCIS SYDNEY GARFORD, OF LOUGHEED, ALBERTA, CANADA.

FENCE-WIRE STAPLE.

Application filed June 14, 1923. Serial No. 645,391.

To all whom it may concern:

Be it known that I, FRANCIS S. GARFORD, a subject of the King of Great Britain, residing at Lougheed, in the Province of Alberta and Dominion of Canada, have invented new and useful Improvements in Fence-Wire Staples, of which the following is a specification.

This invention relates to wire fence staples, and one object of the invention is to provide a staple of simple construction by means of which fence wires may be easily, quickly and securely fastened to the fence posts.

Another object of the invention is to provide a staple which, when driven into the post, will be securely anchored therein against rotation or withdrawal, thereby maintaining the wire supporting means thereof in fixed position, and which may be driven into small posts without liability of splitting them.

Still another object of the invention is to provide a staple which removably holds the fence wire, thus enabling wires to be applied and removed without withdrawing the staples from the posts, which permits of the application and removal of wires without the necessary use of tools, but which in the event of the use of tools for convenience, will allow a simple form of tool or implement to be readily applied and used in applying or releasing a wire, and which may be manufactured and sold at a low cost.

The invention consists of the features of construction, combination and arrangement of parts, hereinafter fully described and claimed, reference being had to the accompanying drawing, in which:—

Figure 1 is a top plan view showing a staple as applied for use in securing a fence wire to a post.

Figure 2 is a side elevation of the staple detached.

Figure 3 is a top plan view thereof.

Figures 4, 5, 6 and 7 are views of modified forms of the invention.

In carrying my invention into practice, I provide a staple made of sheet metal and comprising a body portion 1, in the form of a substantially flat rectangular plate, having at one end an extension 2 terminating in a spur 3. This spur 3 is formed of a portion of the metal from which the body is made, which portion of the metal, at its point of

intersection 4 with the extension 2, is quarter twisted to dispose the spur 3 in a plane at right angles to the plane of the body portion or plate 1. This spur 3 is preferably of the form disclosed, that is, substantially spear-shaped, and is adapted to be driven into the fence post to hold the staple fixed thereto. One of the longitudinal edges of the spur is provided with a plurality of teeth 5 projecting laterally therefrom, two teeth 65 being shown in the present instance, which project beyond opposite sides of the spur. These teeth yield inwardly when the spur is driven into the fence post and then spring outwardly and embed themselves in the 70 post to hold the staple firmly in position and against any possibility of casual extraction.

The body 1 is provided on opposite sides of its longitudinal center with wire retaining hooks 6 and 7. These hooks face in opposite directions, one forwardly and the other rearwardly, and their bight portions are arranged on opposite sides of the line of extension of the fence wire 8 across the 80 staple body, while their bill portions are arranged to overlap said line and overhang the wire. The said bill portions of the hooks have their free edges cut away on oblique lines as indicated at 9, to form a 85 passageway at such an angle as to require the wire 8 to be disposed diagonally of the staple body in the operations of applying or removing it, or to require the portions of the wire on opposite sides of the respective 90 hooks and beyond the same to be sprung successively in reverse directions to clear the bills of the hooks before the wire can be removed. By this means provision is made to permit the wire to be readily and conveniently placed in position or removed from the staple by proper manipulation, while at the same time preventing it from casually getting out of position and becoming displaced. The body portion 1 has a straight outer edge 95 100 adapting it to form a head to squarely receive the blows from a hammer or like tool, whereby the spurs 3 of the staple may be readily and conveniently driven into the side of a fence post 11.

The mode of applying the staple to the fence post will be readily understood, and it will be seen that the staple may be applied to the post after the wire is fitted therein or the staple applied and the wire 110

- then applied thereto by proper manipulation. One advantage of the construction of this staple is that it not only allows convenient application of the wire 8, but also 5 permits of its ready and convenient removal whenever repairs or replacements are necessary, while at the same time effectually preventing any accidental displacement of the wire. Another advantage of the device is 10 that the flattened form of the spur 3 effectually prevents the staple turning or twisting in the fence post and thus getting out of proper position or alignment, while the spurs 3 prevent it from working loose. 15 A further advantage of the device is that the plate 1 allows proper blows of a hammer to be applied in driving the staple, and it also affords a firm and substantial support for the other parts of the staple, thus providing a staple of maximum strength and 20 durability. The construction described adapts a fence wire to be applied and removed without the use of tools, but to facilitate application or extraction of a wire any 25 simple form of tool, such as a nail or the like may be used, the flattened body 1 providing a shelf which allows such tool to be employed with convenience in forcing the wire 8 into or out of position. 30 In Figures 4 and 5 the staple is formed of a length of wire bent to provide limbs 11 and 12 connected by a bight portion 13. As shown, the outer portion of limb 11 is flattened to form the spur 3^a having the 35 teeth 5^a, while the limb 12 is twisted to form the reverse wire receiving hooks 6^a and 7^a. In Figures 6 and 7 the staple is also formed of wire, its body being U-shaped, having parallel limbs 11^a and 12^a providing a wire 40 retaining passage 14, while the free ends of

said limbs are flattened to form the spurs 3^b and teeth 5^b.

Having thus fully described my invention, I claim:—

1. A fence wire staple formed of sheet 45 metal and comprising a substantially rectangular body providing a driving head, an extension at one end of the body, a spur projecting from said extension at right angles thereto, said spur comprising a flat 50 plate arranged at right angles to the body and having teeth to prevent its extraction, and hooks upon the body at opposite sides of said extension.

2. A fence wire staple formed of sheet 55 metal and comprising a substantially rectangular body providing a driving head at one end, the opposite end of said body being pointed and the pointed portion twisted to substantially 90°, and hooks inwardly from 60 the head of said body and at the lateral edges thereof and disposed in opposite directions.

3. A fence wire staple comprising a substantially straight flat body one end of 65 which is squared off to provide a driving head, the opposite end of said body being pointed and twisted to substantially 90° to the body, retaining spurs on said pointed portion, oppositely disposed hook members 70 on the sides of said body inwardly from the ends thereof, and the ends of said hook members cut away at equal angles in the same direction.

In testimony whereof I affix my signature 75 in presence of two witnesses.

FRANCIS SYDNEY GARFORD.
